CARLO SCHLEIFER, OF NOVARA, ITALY.

DEVICE FOR DELIVERING THE TUFTS OF TEXTILE FIBERS FROM COMBING MACHINES HAVING INTERMITTENTLY-ROTATING NIPPER DRUMS.

Application filed November 28, 1927, Serial No. 236,254, and in Germany December 6, 1926.

Combing machines for textile fibers having two or more drums (Schleifer's system U. S. Pat. 1,408,780, 7 March 1922, and U. S. Pat. 1,425,059, 8 August 1922) which have an intermittent rotary motion and are provided at their periphery with a plurality of nippers are already known. The nippers are capable of being closed and opened at definite intervals for seizing and holding the tufts of fibers 5 or for releasing them as required. With this arrangement the fiber tufts to be treated pass to the nippers of successive drums, are combed at their forward and rear ends by rotating combing drums and are finally delivered by 10 the nippers of the last drum to a device by which they are conveyed away.

Now the present invention has for its object to provide such a device for conveying away the combed fiber tufts from the combing 20 machine of the kind described above. The device consists substantially of a delivery cylinder which is arranged parallel to the nippers which are in the discharging position and a pressure applying cylinder which can be caused to rotate through making contact with the delivery cylinder and is so arranged as also to be capable of rocking about the axis of the said cylinder together with a feed cylinder which is also capable of being rotated 25 through being brought in contact with a surface arranged co-axially with the delivery cylinder and fixed rigidly to the same. The motion of the whole arrangement of rocking cylinders consists of a rocking motion, namely 30 a forward motion towards the nippers to be discharged, while the nipper drum of the combing machine is stationary, and a return rocking motion during the intermittent motion of the said drum. Means are also provided for preventing the delivery or paying 35 out cylinder taking part in the forward motion of the rocking of the whole rocking device and for enabling the delivery cylinder to take part only in the first portion of the 40 backward motion. Owing to this arrangement, the delivery cylinder remains stationary during the forward motion and only the pressure applying cylinder and the feed cylinder rotate, so that the former nips the 45 tufts to be delivered and the latter imparts to the travelling band or web of fibers a translation in a positive direction. On the contrary during the first portion of the return motion the two cylinders as a whole rock 50 only, without rotating, together with the de-

livery cylinder and in this way determine the motion of the tuft now delivered with respect to the next tuft to be delivered. In the last portion of the return motion the delivery cylinder is again brought to rest and the rocking cylinders again commence to rotate, but in the opposite direction, for which reason the feed cylinder only partially neutralizes the forward motion previously imparted to the web of fibers.

A constructional form of the invention is shown diagrammatically in the accompanying drawing and is given only as an example. Figs. 1, 2 and 3 show in side elevation, partly in section, all the main parts of the delivery device in three different working positions. Fig. 4 shows the same device in front elevation, partly in section. The diagrammatic view shown in Fig. 5 represents the successive positions of the various parts of the delivery device and Figs. 6, 7 and 8 show modified forms of the device.

In Figs. 1-4 of the drawing, 1 is the last drum of the combing machine having nippers uniformly distributed on the periphery, 80 said nippers, which grip the fibers, having jaws 2 and 3 one of which is fixed whilst the other is movable. The drum 1 is arranged so as to rotate loosely on its shaft 4 and has an intermittent rotary motion imparted to it in 85 the direction of the arrow α shown in Fig. 3, the drum being rotated regularly during each partial revolution through the distance between two successive nippers, for instance by means of an arm 5 arranged so as to rock on 90 the shaft 4 and a pawl 5'' which is pivoted on the arm 5 and is capable of engaging with a ratchet wheel 1' fixed to the drum 1. A detent 5^a which is pivoted on a pin 5^b fixed to the frame of the machine and is capable of engaging in the notches of the ratchet wheel 1' 95 serves the purpose of preventing the drum 1 from turning in the reverse direction.

The delivery device according to the present invention comprises the delivery cylinder 6, the pressure applying cylinder 7 which is parallel to the cylinder 6 and the feed cylinder 9 which, in the constructional form shown in Figs. 1-4, together with a second similar cylinder, not shown, acts as a 100 support for an ordinary endless conveyor band 8 for the removal of the fibers. The cylinder 6 is loosely rotatable on the shaft 10, which is parallel to the shaft 4 and is journaled in suitable arms 11 forming part of 105 110

the frame of the machine. The pressure applying cylinder 7 and the feed cylinder 9 are arranged so as to rock together about the shaft 10 and for this purpose their shafts are journalled in two arms 12 constituting a carrier keyed to the ends of the shaft 10. The cylinder 7 is in direct contact with the cylinder 6 and rolls on the same during the rocking motion. For securing a better contact 10 between the two cylinders longitudinal flutings are preferably provided on the peripheral surface of both cylinders. In the constructional form described, the cylinder 9 for the band 8 is not in contact with the cylinder 6, but a toothed wheel 9' is keyed on the shaft of the cylinder 9, which wheel meshes with a toothed wheel 6' fixed to the cylinder 6, so that on the cylinder 9 rocking with respect to the cylinder 6, the cylinder 9 15 will also have a rotary motion imparted to it. In order that the endless conveyor band 8 shall always remain taut during the rocking motion of the feed cylinder 9, it is necessary, as will be readily understood, that the rear 20 cylinder (not shown in the drawing), by which the conveyor band is supported, shall perform a similar rocking motion.

The rocking motion of the two cylinders 7 and 9 is imparted to them by a connecting 25 rod 13 which is pivoted at 5' to an extension 5" of the rocking arm 5 and at 12' to an arm 12 keyed to the shaft 10.

The cylinder 6, which is loosely rotatable on the shaft 10, is permanently prevented from 30 rotating in the clockwise direction by a detent 14 which is mounted on an arm 11 and is kept by a spring 18 in engagement with a fine toothed ratchet wheel 15 fixed to the cylinder 6. The cylinder 6 is also generally 35 prevented from rotating in the other direction by a second detent 16 which is also pivoted to the arm 11, is kept by the same spring 18 in engagement with a ratchet wheel 17, which is also fixed to the cylinder 6, and has teeth of greater pitch. The 40 detent 16 can be temporarily lifted out of engagement with the ratchet wheel 17 this being effected by any of the stop pins 19 which are provided in suitable positions on the periphery of the drum 1 in the vicinity of each set 45 of nippers, for the purpose of striking an arm 16' of the detent 16 and thereby releasing the cylinder 6 temporarily for rotating in the counter-clockwise direction.

The device operates in the following manner. When a closed pair of nippers 2, 3 with a tuft —a— of combed fibers comes to rest in the position shown in Fig. 1, at the end of each partial rotation of the drum 1 of 50 the combing machine, the forward portion of this tuft will lie closely against the web —b— formed by the previously delivered tufts on the delivery cylinder 6, and prolonged by the web —b'— already deposited on the endless conveyor band 8. Owing to the position

occupied at this moment by the rocking arm 5 the two cylinders 7 and 9 are at their greatest distance from the drum 1. This position of the parts is shown in Fig. 1, which corresponds to the position indicated by I in Fig. 5. At the same time one of the stop pins 19 strikes the arm 16' of the detent 16 causing the latter to be lifted out of engagement with the ratchet wheel 17. When the arm 5 performs its idle motion until it reaches the 75 position shown in Fig. 2, during which the drum 1 is held in the position in which it happens to be, the cylinders 7 and 9 perform their forward motion —a— (Fig. 5) until they reach the position in which they are nearest to the drum 1, as shown in Fig. 2, and as indicated by II in Fig. 5. Since the cylinder 6 cannot take part in the forward motion —a—, as it is prevented from doing so by the 80 detent 14 engaging in the ratchet wheel 15, the effect will be that the two cylinders 7 and 9 will rotate, the former rolling around the cylinder 6, until it has gripped the forward end of the freshly delivered tuft —a— and has pressed it against the web —b— and the latter owing to the toothed wheel 9', rolling around the toothed wheel 6', whereby the endless conveyor band 8 is fed forward by the amount —S— in the positive direction of its 85 forward motion (Fig. 5).

When the arm 5 rocks back from the position shown in Fig. 2 into that shown in Fig. 1, causing the drum 1 to rotate, the two cylinders 7 and 9 will also swing back into the 90 position shown in Fig. 1. This return motion comprises the two phases — β — and — γ — (Fig. 5). In the first part — β — of the motion which extends approximately into the position shown in Fig. 3, indicated by III in Fig. 5, the delivery cylinder 6, owing 95 to the fact that detent 16 is not in engagement with the ratchet wheel 17, will during the rocking motion be carried along together with the parts 7 and 9 so that neither the cylinder 7 will roll on the drum 6 nor the toothed wheel 9' on the toothed wheel 6'. This rocking motion of the cylinder 6 continues until the bottom of a notch in the ratchet wheel 17 strikes against the end of the detent 16 which has in the meantime been able to enter 100 into engagement with the ratchet wheel 17, owing to the stop pin 19 having passed the arm 16' of the detent 16. It follows that the angle through which the cylinder 6 is turned is equal to the angle — β — or the distance between two teeth of the ratchet wheel 17. The same angular motion will have been imparted to the last tuft —a— with regard to the position occupied by it at the moment it was delivered, so that the following tuft 105 —a'— (Fig. 3), on being brought against the cylinder 6, is displaced with respect to the tuft —a— in front of it by a linear distance equal to the length of the arc subtended at the periphery of the cylinder 6 by the angle 110

$-\beta$. In this way successive tufts are given a desired relative position so that they overlap one another to form the web $-b, b'$.

In the second part $-y$ of the return motion, which extends as far as the position shown in Fig. 1, the cylinder 7, owing to the fact that cylinder 6 is again brought to rest, will roll around the cylinder 6 and the wheel 9' around the wheel 6'. During this return motion the cylinder 9 will impart to the endless band 8 a motion $-S'$ in the negative sense, or in other words, a backward motion (Fig. 5) which, however, is smaller than the motion $-S$ previously imparted to it in the opposite direction as a forward feed motion. The band 8 will thus finally have had imparted to it a forward feed motion $-s$ which must be equal to the length of the arc on the periphery of the cylinder 6 corresponding to the angle $-\beta$, which is effected by the diameter of the wheels 6' and 9' being suitably selected with respect to the angles $-\beta$ between the teeth of the ratchet wheel 17. By suitably varying the size of the angle $-\beta$ and the diameters of the wheels 6' and 9' any desired overlapping of successive tufts may be obtained, according to the kind of fibers used and their length.

The same result may be obtained if, as shown in the modification according to Fig. 6, the pressure applying cylinder 7 be omitted and the feed cylinder 9 be so arranged that it can roll around the delivery cylinder 6 together with the endless band 8. In practice, however, the provision of a separate pressure applying cylinder 7 is to be preferred, as the cylinder 7 may be made of relatively small diameter so that it is capable of being brought close up to the nippers to be emptied, and can thus nip fairly short tufts.

The device for conveying the web of fibers $-b'$ may also be made so as to remain in the same position in which case they would be independent of the feed cylinder 9, which is arranged to rock, as shown in Figs. 7 and 8. In Fig. 7 the endless conveyor band 8 is stretched over two cylinders, only one 8^a of which is shown, both cylinders being journaled in fixed bearings. In the constructional form shown in Fig. 8 the motion of the web $-b'$ is produced by a roller 8^a and a counter-roller 8^b which are also journaled in fixed bearings. In both cases the portion $-b''$ of the web of fibers sags down freely.

It will be seen that the invention is in no way limited to the constructional forms described and shown, but that without departing from the underlying idea of the invention, the device may be modified in any way to meet all requirements and circumstances met with in practice.

I claim:

1. In a device of the character described, the combination with an intermittently ro-

tating drum, and a series of nippers carried thereby, of a delivery cylinder, a feed cylinder, in parallel relation to the delivery cylinder, a carrier for the feed cylinder, means to rock the carrier about the axis of the delivery cylinder, and means operable by the movement of the carrier to rotate the feed cylinder. 70

2. In a device of the character described, the combination with an intermittently rotating drum, and a series of nippers carried thereby, of a delivery cylinder, a pressure cylinder in operative relation to the latter, a feed cylinder, in parallel relation to the delivery and pressure cylinders, a carrier for the pressure and feed cylinders, means to rock the carrier about the axis of the delivery cylinder and means operable by the movement of the carrier to rotate the feed cylinder. 75

3. In a device of the character described, the combination with an intermittently rotating drum, and a series of nippers carried thereby, of a delivery cylinder, a pressure cylinder in contact therewith, a feed cylinder, a carrier for the pressure and feed cylinders, means to rock the carrier about the axis of the delivery cylinder, and means connected with the feed and delivery cylinders operable by the movement of the carrier to impart a rotary movement to the feed cylinder. 80

4. In a device of the character described, the combination with an intermittently rotating drum, and a series of nippers carried thereby, of a delivery cylinder, a pressure cylinder in contact therewith, a feed cylinder, a carrier for the pressure and feed cylinders, means to rock the carrier about the axis of the delivery cylinder, and intermeshing gears connecting the delivery and feed cylinders whereby rotation is imparted to the latter during the movement of the carrier. 90

5. In a device of the character described, the combination with an intermittently rotating drum, and a series of nippers carried thereby, of a delivery cylinder, a pressure cylinder in contact therewith, a feed cylinder, a carrier for the pressure and feed cylinders, means to rock the carrier about the axis of the delivery cylinder, intermeshing gears connecting the delivery and feed cylinders whereby rotation is imparted to the latter during the movement of the carrier, and means to lock the delivery cylinder against rotation during the movement of the carrier in one direction. 110

6. In a device of the character described, the combination with an intermittently rotating drum, and a series of nippers carried thereby, of a delivery cylinder, a pressure cylinder in contact therewith, a feed cylinder, a carrier for the pressure and feed cylinders, means to rock the carrier about the axis of the delivery cylinder, and an endless conveyor carried on and moved by the feed cylinder. 120

7. In a device of the character described, the combination with an intermittently ro-

tatable drum, and a series of nippers carried thereby, of a delivery cylinder, a feed cylinder parallel thereto, a carrier for the feed cylinder, means to rock the carrier about the axis of the delivery cylinder, means operatively connecting the delivery and feed cylinders whereby the movement of the carrier imparts rotation to the feed cylinder, a ratchet wheel fixed on the latter, and a spring loaded detent engaging the ratchet wheel to lock the delivery cylinder against rotation during the forward movement of the feed cylinder.

8. In a device of the character described, the combination with an intermittently rotatable drum and a series of nippers carried thereby, of a rotatable delivery cylinder, a pressure cylinder in contact therewith, a feed cylinder, a carrier for the pressure and feed cylinders, means to rock the carrier about the axis of the delivery cylinder, gears connecting the delivery and feed cylinders, means for locking the delivery cylinder against rotation in one direction during the forward movement of the carrier, and means to lock the delivery cylinder against rotation in the opposite direction during a part of the backward movement of the carrier.

9. In a device of the character described, the combination with an intermittently rotatable drum, and a series of nippers carried thereby, of a rotatable delivery cylinder, a pressure cylinder in contact therewith, a feed cylinder, a carrier for the pressure and feed cylinders, means to rock the carrier about the axis of the delivery cylinder, gears connecting the delivery and feed cylinders, means to lock the delivery cylinder against forward rotation, means to lock the delivery cylinder against backward rotation, and mechanism controlled by the movements of the drum to release the delivery cylinder from the last named locking means during the first portion of the backward movement of the carrier.

10. In a device of the character described, the combination with an intermittently rotatable drum and a series of nippers carried thereby, of a rotatable delivery cylinder, a pressure cylinder in contact therewith, a feed cylinder, a carrier for the pressure and feed cylinders, means to rock the carrier about the axis of the delivery cylinder, gears connecting the delivery and feed cylinders, a detent to lock the delivery cylinder against rotation in one direction, an auxiliary detent to lock the delivery cylinder against rotation in the opposite direction, and means on the drum for holding the auxiliary detent out of locking position during part of the return movement of the carrier.

11. In a device of the character described, the combination with an intermittently rotatable drum, and a series of nippers carried thereby, of a rotatable delivery cylinder arranged parallel to the drum, a pressure

cylinder in contact with the delivery cylinder, a feed cylinder, a carrier for the pressure and feed cylinders, means to intermittently rotate the drum, and means to rock the carrier towards the drum during a period of rest of the latter and rock the carrier away from the drum during the movement of the latter.

12. In a device of the character described, the combination with an intermittently rotatable drum and a series of nippers carried thereby, of a rotatable delivery cylinder arranged parallel to the drum, a pressure cylinder in contact with the delivery cylinder, a feed cylinder, a carrier for the pressure and feed cylinders, means to intermittently rotate the drum, means to rock the carrier towards the drum during a period of rest of the latter and rock the carrier away from the drum during the movement of the latter, means to lock the delivery cylinder against rotation during movement of the carrier towards the drum, and means operatively connecting the delivery and feed cylinders whereby rotary motion is imparted to the feed cylinder during the movement of the carrier towards the drum.

13. In a device of the character described, the combination with an intermittently rotatable drum, and a series of nippers carried thereby, of a rotatable delivery cylinder arranged parallel to the drum, a pressure cylinder in contact with the delivery cylinder, a feed cylinder, a carrier for the pressure and feed cylinders, means to intermittently rotate the drum, means to rock the carrier towards the drum during a period of rest of the latter and rock the carrier away from the drum during the movement of the latter, and means to permit rotation of the delivery cylinder during a portion of the movement of the carrier away from the drum.

14. In a device of the character described, the combination with a drum and a series of nippers carried thereby, of actuating means to intermittently rotate the drum in one direction, a delivery cylinder adjacent the drum, a shaft on which the cylinder is loosely mounted, carrier arms fixed to the shaft, pressure and feed cylinders journaled in said arms, means operated by the actuating means for oscillating said arms to and from the drum, gears on the delivery and feed cylinders operatively connecting them together, a pawl and ratchet mechanism for preventing rotation of the delivery cylinder in one direction, an auxiliary pawl and ratchet mechanism for limiting the rotation of the delivery cylinder in the opposite direction, and means on the drum for actuating the auxiliary pawl whereby the delivery cylinder is rotatable by the carrier when the latter is moved away from the drum.

15. In a device of the character described, the combination with a drum and a series of

- nippers carried thereby, of actuating mechanism for intermittently rotating the drum in one direction, a shaft parallel to the axis of the drum, a delivery cylinder rotatable on the shaft, carrier arms fixed to the latter, a pressure cylinder journaled in the arms in contact with the delivery cylinder, a feed cylinder journaled in said arms, gears connecting the delivery and feed cylinders, 10 means operated by the drum actuating mechanism for oscillating the carrier arms to and from the drum, means for locking the delivery cylinder during the movement of the arms towards the drum to impart rotation 15 to the pressure and feed cylinders throughout said movement, and auxiliary means to lock the delivery cylinder against rotation during a portion of the return movement of the carrier from the drum.
- 20 16. In a device of the character described, the combination with a drum and a series of nippers carried thereby, of actuating mechanism for intermittently rotating the drum in one direction, a shaft parallel to the axis

of the drum, a delivery cylinder rotatable on the shaft, carrier arms fixed to the latter, a pressure cylinder journaled in the arms in contact with the delivery cylinder, a feed cylinder journaled in said arms, gears connecting the delivery and feed cylinders, 25 means operated by the drum actuating mechanism for oscillating the carrier arms to and from the drum, means for locking the delivery cylinder during the movement of the arms towards the drum to impart rotation 30 to the pressure and feed cylinders throughout said movement, auxiliary means to lock the delivery cylinder against rotation during a portion of the return movement of the carrier from the drum, and means on the latter 35 for controlling the operation of the auxiliary locking means whereby said delivery cylinder is free to rotate during the movement of the drum.

In testimony that I claim the foregoing 40 as my invention, I have signed my name.

CARLO SCHLEIFER.
